US00D858173S

(12) United States Design Patent (10) Patent No.: US D858,173 S
Hecker et al. (45) Date of Patent:  Sep. 3, 2019

(54) GRILLING APPARATUS

(71) Applicants: Frank Hecker, Königswinter (DE); Franz Dieter Konzen, Bad Honnef (DE); Marc Kirwald, Königswinter (DE); BEEFER GRILLGERÄTE GMBH, Bad Honnef (DE)

(72) Inventors: Frank Hecker, Königswinter (DE); Franz Dieter Konzen, Bad Honnef (DE); Marc Kirwald, Königswinter (DE)

(73) Assignee: BEEFER GRILLGERÄTE GMBH, Bad Honnef (DE)

() Term: 15 Years

(21) Appl. No.: 35/502,729

(22) Filed: Jan. 16, 2017

(80) Hague Agreement Data

Int. Filing Date: Jan. 16, 2017

Int. Reg. No.: DM/095307

Int. Reg. Date: Jan. 16, 2017

Int. Reg. Pub. Date: Mar. 31, 2017

(30) Foreign Application Priority Data
